DESCRIPTION

U.S. PATENT DOCUMENTS

FIG. 1 is a perspective view of the towel bar of the invention;

D388,271 S * 12/1997 Moore D6/546
D394,972 S * 6/1998 Moore et al. D6/550
D436,776 S * 1/2001 Chen D6/524

FIG. 2 is a side view of the towel bar of FIG. 1;
FIG. 3 is a top view of the towel bar of FIG. 1;
FIG. 4 is a front view of the towel bar of FIG. 1;
FIG. 5 is a bottom view of the towel bar of FIG. 1; and,
FIG. 6 is a rear view of the towel bar of FIG. 1.
